His Attorney.

UNITED STATES PATENT OFFICE

CHARLES HATAY, OF BERLIN-CHARLOTTENBURG, GERMANY, ASSIGNOR TO GENERAL ELECTRIC COMPANY, A CORPORATION OF NEW YORK

MERCURY SWITCH WITH PLUNGING CORE

Application filed May 1, 1929, Serial No. 359,653, and in Germany May 8, 1928.

My invention refers to mercury switches and more especially to the kind of switches comprising a container enclosing a body of mercury and a magnetizable body floating 5 in the mercury, this body being depressed deeper into the mercury by means of a magnetic field acting in the vicinity of the container. By thus depressing the floating body into the mercury, the mercury level in 10 the container is caused to rise and bridge the distance between the ends of the two electrodes.

As is well known to those skilled in the art switch devices of this kind require for their 15 operation a comparatively large amount of energy in order to overcome the considerable lifting forces exerted on the iron core by the mercury. In addition this arrangement involves the disadvantage that the current 20 is interrupted between the mercury and the electrodes whereby the electrode material is readily dissolved in the mercury. The making and breaking of the circuit also occurs in proximity to the glass wall of the container, 25 which is thereby soon destroyed.

It is an object of my invention to provide a switch of this type, which is free from the drawbacks enumerated above.

In order to enable the plunging body or 30 core to be depressed into the mercury with the least possible amount of energy, I employ a core consisting partly of iron and partly of a vessel containing mercury. The mercury in the vessel is used for making 35 and breaking the contact and therefore a contact making and breaking between the mercury and the electrodes is avoided. Switching is here effected within the mercury vessel mounted on the plunging core so 40 that the container wall is not affected thereby. This small vessel mounted on the iron core can be made of quartz or some other material resistive against the action of the arc without requiring great cost.

45 In the drawing affixed to this specification

and forming part thereof two modifications of a switch embodying my invention are illustrated diagrammatically by way of example.

In the drawing

Fig. 1 is an axial section of the first modification, while

Fig. 2 is a similar view of the second form.

Referring first to Fig. 1, 1 is a tubular container and 2 and 3 are metal wires extending axially into this container from the top and bottom thereof, respectively, and forming the electrodes. 4 is the body of mercury partly filling the container and 5 is a tubular iron core floating in the mercury. A 55 small vessel made of quartz or the like is mounted on top of the iron core. It consists of an inner tube 7 closed at the bottom, an outer tube 8 and a flange 6 connecting the top ends of the tubes. The inner tube 7 60 extends into the iron core 5, while the outer tube 8 surrounds the outer wall thereof. The core 5 and the quartz vessel mounted thereon are immersed in the mercury so far that only the top ends are free. The inner 65 tube 7 of the vessel is filled with a body of mercury 9.

If by means of a magnetic field surrounding the container 1 the core 5 is pulled down into the mercury, the mercury in the container 1 will rise above the flange 6 and will unite with the mercury 9 in the tube 7, so that the contact is formed between the two mercury bodies, while the electrodes 2 and 3 do not take part therein, being always immersed in the two mercury bodies. On the core rising again, the mercury in the tube 7 will separate from the mercury in the container 1 at the flange 6.

In this manner a very large cross-sectional area of mercury is available for current transmission, the outer body of mercury overflowing the flange 6 from all sides and in consequence thereof no perceptible heating of the mercury will take place. When breaking the 90

current, such break will take place only at one point, at which the two bodies of mercury separate at the last moment. However, such break will occur always at a different point, 5 so that even after frequent switching no injurious local heating of the flange 6 can occur.

In the modification illustrated in Fig. 2 the iron core 15 has the form of a tube of greater diameter. The quartz vessel is formed again 10 of two concentric tubes 16 and 18, the inner one being of less height than the outer one and the two tubes being connected with each other by an annular bottom 19. The vessel is filled with a body of mercury 17 up to the 15 top edge of the inner tube 18. If the iron core 15 is depressed by the action of a solenoid 20 which surrounds the container 1, the mercury level in the container 1 rises in the tube 18 until the mercury flows over the top 20 edge of the tube 18 and unites with the body of mercury 17 in the vessel. Owing to the fact that the outer tube is longer than the inner tube of the vessel, the arc which may 25 form when switching is kept away from the walls of the glass container 1.

I wish it to be understood that I do not desire to be limited to the exact details of construction shown and described for obvious modifications will occur to a person skilled 30 in the art.

In the claims affixed to this specification no selection of any particular modification of the invention is intended to the exclusion of other modifications thereof and the right to 35 substantially make claim to any modification not covered by these claims is expressly reserved.

I claim:—

1. A mercury switch comprising a container, a body of mercury in said container, a core floating on said body, a vessel on said core, said vessel having a continuous horizontal rim, another body of mercury in said vessel, 45 said bodies of mercury merging and separating on said rim upon appropriate movement of said core, and an electrode extending into each body of mercury.

2. A mercury switch comprising a container, a body of mercury in said container, a core floating on said body, a vessel of annular cross-section on said core, another body of mercury in said vessel, said vessel having a horizontal rim on which said bodies of mercury merge and separate on appropriate movement of said core, and an electrode extending into each body of mercury.

3. A mercury switch comprising a container, a body of mercury in said container, a core floating on said body, a vessel of annular cross-section on said core, another body of mercury in said vessel, the inner wall of said vessel being lower than the outer one and having a horizontal rim on which said mercury bodies merge and separate on appropriate

movement of said core, and an electrode extending into each body of mercury.

4. A mercury switch comprising a container, a body of mercury in said container, a core floating on said body, a vessel supported by said core, another body of mercury in said vessel, a passage through said core for mercury flow to connect said bodies, and an electrode extending into each body of mercury, said vessel having a continuous horizontal rim on which said mercury bodies merge and separate on appropriate movement of said core.

5. A mercury switch comprising a container, a body of mercury in said container, a core floating on said body, a vessel of arc resisting material on said core, a body of mercury in said vessel, said vessel having a continuous horizontal rim on which said bodies of mercury merge and separate on appropriate movement of said core, and an electrode terminating in each of said bodies of mercury.

6. A mercury switch comprising a container, a body of mercury in said container, a magnetic core floating on said body, a vessel of annular cross-section on said core, another body of mercury in said vessel, the inner wall of said vessel being lower than the outer wall thereof and having a continuous horizontal rim on which said bodies of mercury merge and separate on appropriate movement of said core, and an electrode extending into each of said bodies of mercury.

In testimony whereof I affix my signature.

CHARLES HATAY.

100

CERTIFICATE OF CORRECTION.

Patent No. 1,861,630.

June 7, 1932.

CHARLES HATAY.

It is hereby certified that error appears in the printed specification of the above numbered patent requiring correction as follows: Page 2, line 35, for the word "substantially" read subsequently; and that the said Letters Patent should be read with this correction therein that the same may conform to the record of the case in the Patent Office.

Signed and sealed this 22nd day of November, A. D. 1932.

(Seal)

M. J. Moore,
Acting Commissioner of Patents.
